TOILET CASE

George Wise, Washington, D. C.

Application August 25, 1941, Serial No. 408,251

5 Claims. (Cl. 248—212)

My invention relates to the disposition of toilet articles such as razors, razor blades, shaving soap and the like, and has among its objects and advantages the provision of an improved toilet case, wherein the case provides a handy container for such articles when carried as baggage, and in which novel means are incorporated for attaching the open case to the faucet structure of a lavatory to render the articles conveniently accessible while making the toilet.

In the accompanying drawing:

Figure 1 is a perspective view illustrating the invention associated with a faucet structure;

Figure 2 is a sectional detail view illustrating the faucet clamp;

Figure 3 is a view illustrating the faucet clamp pivoted to an inoperative position inside the case;

Figure 4 is a top plan view of the faucet clamp;

Figure 5 is a view similar to Figure 2 but illustrating the clamp structure rotated ninety degrees; and

Figure 6 is a perspective view of a clamp latch.

In the embodiment selected for illustration, I make use of a toilet case 10 which may be folded transversely and closed through the medium of the usual slide fastener 12. Such a case is preferably formed of leather with appropriate lining. Inside the case 10 and transversely thereof is located a clamp structure 14, which clamp structure is positioned equal distances from the ends of the case. The two end portions of the case fold adjacent the clamp structure 14.

The clamp structure 14 comprises two parallel walls 16, end walls 18 and transverse walls 20 spaced from the respective walls 18 to provide small compartments 22 suitable for containing small articles such as razor blades. A bottom wall 24 is attached to the side walls 16, the end walls 18 and the walls 20. To the bottom 24 is pivotally connected a tubular member 26, as at 28, this member being provided with an annular flange 30 at its end remote from the pivot 28 to slidably engage a cam member 32. While the member 32 is slidably guided by the flange 30, the member is restrained from relative rotary movement by reason of a key 34 on the flange 30 extending into a longitudinal groove 36.

Two diametrically opposed slots 38 are provided in the member 32, which slots extend longitudinally thereof and have their bottom walls widened to provide bores 40 intersected by the respective slots 38. Bores 40 are arranged in converging relationship in the direction of the lower end of the member 32, see Figure 2. Two 55

clamp arms 42 are pivotally connected one with the other intermediate their ends, as at 44. Each arm 42 is provided with a ball 46 slidably receivable in one bore 40, and the adjacent lengths of the arms are also slidably guided in the slots 38. Each arm 42 is bent into loop formation at its opposite end and is provided with a rubber sleeve covering 50. These loops are of slight curvature when viewed according to Figure 2 and have clamping engagement with the faucet 52.

Means for applying clamping pressure to the faucet-engaging loops 50 comprises a compression spring 54 having one end loosely receivable in a bore 56 in the member 32 and its other end engaging a cross piece 58 having its ends secured to the tubular member 26. Thus the spring 54 is tensioned against the member 32 urging the member outwardly with respect to the tubular member 26. Upward movement of the member 32, as when viewing Figure 2, imparts pivotal movement to the arms 42 by reason of the angularity of the bores 40 for clamping the loop formations 50 firmly upon the faucet 52. In placing the clamp on the faucet 52, the member 32 is pressed inwardly of the member 36, which may be accomplished by the thumb of the hand with two fingers of that hand extended underneath ears 58 projecting laterally from the tubular member 26. With the loop formation 50 spread sufficiently far to receive the faucet 52, pressure is released from the member 32 which permits the spring 54 to shift the member 32 to bring the loop formations into clamped engagement with the faucet.

In carrying the case as baggage, the tubular member 26 is pivoted to the position of Figure 3, which brings the arms 42 inside the compartment 60. To securely latch the member 26 against accidental pivotal movement when the case is clamped to the faucet, the tubular member 26 is provided with a T head 62 depending beneath the bottom 24. A slide plate 64 is provided with a notch 66 in one end thereof for the reception of the T head 62 to latch the tubular member 26 in the position of Figure 2. Plate 64 is slidably guided in channels 68 secured to the outer face of the bottom 24.

The side walls 70 of the case 10 are riveted at 72 to the bottom 24, and the side walls bend about the corners 74 when the case is closed.

The bottom 24 is provided with an opening 76 normally closed by the plate 64 and of sufficient size to permit the arms 42 to pivot therethrough.

Without further elaboration, the foregoing will

so fully illustrate my invention, that others may, by applying current knowledge, readily adapt the same for use under various conditions of service.

I claim:

1. The combination of a case, a clamp attached to the case for mounting the latter on a support, said clamp normally lying inside the case, and means movably connecting the clamp with the case so arranged as to project the clamp exteriorly of the case when the clamp is moved to a predetermined position for connection with said support.
2. The invention described in claim 1 wherein said clamp includes pivotally connected arms spring tensioned against the support.
3. The invention described in claim 1 wherein said clamp includes crossed and pivotally connected arms resiliently pressed against the support.
4. The invention described in claim 1 wherein said clamp includes crossed and pivotally connected arms, a cam member operatively connected with the arms for spreading the latter to receive the support, and resilient means act-

ing on said cam member for yieldingly pressing the arms against the support.

5. The invention described in claim 1 wherein said clamp comprises a rigid wall attached to said case, with the latter foldable over said rigid wall, said rigid wall being provided with an opening, a tubular member pivotally connected with said wall inside the case, a cam member slideable longitudinally in said tubular member and having diametrically opposed slots terminating in grooves arranged in converging relationship one with the other, crossed and pivotally connected arms for connection with the support, each arm having one end slideable in one of said slots, an end formation slideable in one of said grooves, resilient means acting on said tubular member and said cam member for biasing the latter to a predetermined position for yieldingly pressing the other ends of the arms against the support, said arms being movable through said opening through pivotal movement of the tubular member, and a closure means for said opening.

GEORGE WISE.
